BOOKING APPARATUS

Aron Berteus Kornelius Aronsen, Oslo, Norway

Application May 8, 1946, Serial No. 668,291
In Norway January 23, 1943Section 1, Public Law 690, August 8, 1946
Patent expires January 23, 1963

1 Claim. (Cl. 282—29)

1

This invention relates to an appliance for use in book-keeping of the manifolding type.

In so-called double-entry book-keeping systems all items entered in the credit columns of one accounts sheet must be entered also in the debit columns in other accounts sheets and vice-versa, thus it becomes necessary to make at least two entries and in some accounting systems even more. The object of the present invention is to provide an improved form of appliance by means of which debit and credit entries can be made in the appropriate columns of the various accounts sheets, for example, a ledger sheet, day book sheet and customers account sheet, simultaneously, in one operation.

According to the invention the appliance comprises a frame member, a slide movable in said frame member, means for securing or clamping an accounts sheet to said slide and means for securing other accounts sheets to said frame above the slide, characterized in that the slide is adjustably movable relative to the frame by means of a hand operated control member which serves additionally as an indicator for indicating the position of the debit and credit columns of the accounts sheet carried by the slide relative to the debit and credit columns on the accounts sheets clamped to the frame at the various adjusted positions of said slide.

In operating the appliance according to the invention, in connection with one form double entry book-keeping, a ledger sheet is placed on the slide, which by the aid of the hand control member, is adjusted as required to permit the making of entries in any desired column. On top of the ledger sheet is placed a day book sheet which is held in position on the frame member by suitable retaining or clamping means which is independent of the slide and does not hinder its movement. The day book sheets are carboned on that part of the back surface which corresponds to the sundry accounts columns on the front thereof for the purpose hereinafter more fully described. On top of the day book sheet the customers account sheet is placed with a carbon paper underneath, said customers account sheet also being held in position on the frame member by the same means which hold the day book sheet in position. With the various account sheets arranged in this way entries made

2

on the customers account sheet are automatically traced onto the day book sheet and, by suitable adjustment of the slide, provision can be made to ensure that the entries are made also in the appropriate columns of the ledger sheet. As the day book sheet is carboned only at the back of the sundries accounts column, only the entries made in this column will appear on the ledger sheet, thus in one operation entries are made which would normally require four or even more operations.

In order to facilitate the making of entries, an indicating arrangement is provided which displays the headings corresponding to and positioned according to those on the ledger sheet, which is obscured from the operator's view when the day book and customers account sheets are placed on top, and indicates whether the device is properly adjusted for entering items in the appropriate columns of the various accounts sheets. The position of the customers accounts sheet and the day book sheet relative to the ledger sheet is adjusted by moving the slide carrying the ledger sheet by means of the hand control member, according to positions of the various columns indicated by the indicating arrangement showing the heading corresponding to those on the ledger sheet. When the appropriate position of the slide is determined it is automatically retained in that position by a tooth or projection on the hand control member entering a corresponding recess in the frame of the appliance.

In order that the invention may be more clearly understood, one particular embodiment thereof will now be described, by way of example, with reference to the accompanying drawings, wherein:

Fig. 1 is a plan view of the appliance showing the movable ledger sheet in position.

Fig. 2 is a plan view of the underside of the appliance with its supporting base removed and some parts broken away.

Fig. 3 is a plan view showing the relative position of the several documents placed in the appliance during use.

The apparatus comprises a frame having two side members 1, 1a and two end members 2, 2a preferably mounted on a suitable supporting base plate 22.

Between the two side frame members 1 and 1a is mounted a slide 21 adapted to carry a ledger sheet 6 and to slide longitudinally as indicated by the arrows. The slide 21 is arranged to pass underneath the end of frame members 2 and 2a during its sliding movement. Securely attached to one side of the slide 21 is a hand control member 7 by means of which the longitudinal displacement of the slide is effected. The hand control member comprises a springy or resilient arm which passes below the side frame member 1a and projects beyond the outer edge thereof so as to be easily accessible. On the upper surface of the arm of the member 7 is a tooth or projection 8 which is adapted to coact with any one of a series of spaced recesses or notches 24 formed in the underside of the side frame member 1a, whereby said slide 21 can be resiliently retained in any adjusted position relative to the frame. The springy or resilient arm is so arranged that it is automatically urged upwards to hold the tooth or projection 8 in one of said recesses or notches, the member 7 being pressed downwards when it is desired to disengage the tooth or projection from said recess or notch to readjust the slide.

The side frame member 1a is provided with a longitudinal slot or window 9 in which is arranged a strip having marked thereon data corresponding to the various headings on the ledger sheet 6 carried by said slide.

The ledger sheet 6 is immovably secured on the slide 21 by a resilient clamping means operated by a handle 13. The slide itself comprises separate parts which fit one into the other and which are held flush with one another, that is with their upper surfaces in the same plane, by springs 12 which are interconnected by a cross bar 20 and pressed against the underside of the slide by the action of crank pieces 18, 18', 19, 19'. These crank pieces 18, 18', 19, 19' are formed adjacent the ends of shafts 14 and 15 mounted in suitable bearings in the frame and interconnected by links 16 and 17 as shown. Said shafts are adapted to be rotated by the handle 13 formed on one end of the shaft 14. When the handle 13 is turned 90° the crank pieces 18, 18' and 19, 19' will cause a reduced pressure of the springs 12 upon the side parts 25, 26 at each end of the slide so that an opening 23 is obtained between the slide and the side-parts 21. The ledger 6 is then placed with its edges in the openings 23. When the handle 13 is turned further 90° the sideparts 25, 26 will be caused by means of the springs 12 to close the openings 23 and fasten the ledger 6 rigidly to the slide.

The end frame member 2 has hingedly mounted thereon a plate 5 for securing a day sheet 27 and a customers account sheet 29 to the frame member in such a manner that said sheets are positioned above the ledger sheet carried by the slide 21. To ensure that the day sheet and customers account sheet are immovably secured in position on the frame, the said frame member 2 may be provided with studs or pins 3 which coact with corresponding holes 4 in the plate 5 when said plate is in clamping position. If desired the sheets adapted to be clamped by said clamping plate 5 may also be provided with holes adapted to register with the pins 3. Suitable springs 5a are preferably provided to hold the hinged clamping plate 5 firmly in contact with the frame member 2 when in closed position.

In operation a ledger sheet 6 is secured to the slide 21, as above described, and in such a

manner that the various headed columns of said sheet are in line with the corresponding headings indicated in the indicating slot or window 9, whereupon a day book sheet 27 with a customer's account sheet 29 on top and a sheet of carbon paper 28 between the same is clamped to the frame by the clamping means 3, 4, 5 as above described. The appliance is then ready for use.

It will be understood that when the various accounts sheets are thus clamped in the appliance the headings of the ledger sheet, i. e. the lower sheet carried by the slide 21, will be obscured by the day book and customer's account sheets placed on top. When however, it is desired that an entry be made in the ledger sheet the slide 21 is displaced by means of the hand control 7 until said hand control is positioned in front of the column in the indicating window 9 corresponding to the relevant credit column on the ledger sheet. By this means the ledger sheet is moved relative to the customer's account and day book sheets to bring the various debit and credit columns on said sheets into register with the corresponding credit and debit columns of the ledger sheet which is obscured. The desired entry is then made on the top sheet that is the customer's account sheet. As a carbon paper is placed between the customer's account sheet and the day book sheet all entries made on the customer's account sheet will at the same time be made also on the day book sheet. As however, the day book sheet is carboned on its back surface only below the sundries debit and credit columns, corresponding credit and debit entries only will be made on the ledger sheet. Thus all relevant entries will be made on the customer's account sheet, day book sheet and ledger sheet in one operation without certain matters entered on the customer's account sheet appearing unnecessarily on the ledger sheet.

When one customer's account sheet has been completed it is removed from the appliance and another customer's account sheet is clamped in position in the frame for the next entry, said new customer's account sheet of course being so positioned that the entries made thereon will appear on the next lower horizontal column of the day book and ledger sheets.

If desired two windows 10 and 11 may be provided in the side frame member 1 and arranged to display two coloured indicators representing debits and credits, the arrangement being such that the colours are changed by the displacement of the slide 21 to the debit or credit side so as to indicate clearly whether the appliance is adjusted for entering in the debit or credit columns of the ledger sheet.

It will be understood that the invention is not limited to the details of construction herein described and shown in the drawings but that changes, for example in the means for clamping the ledger sheet to the slide, may be made without departing from the scope of the appended claim.

I claim:

A book-keeping appliance of the manifold type comprising in combination a frame, a slide for a journal sheet adjustably movable in the frame, means for securing account sheets to said frame above the slide, a resilient operating handle projecting at the longitudinal side of said slide approximately at the middle thereof, a tooth on said handle for cooperating with a row of re-

cesses in the adjacent edge of said frame, said recesses being arranged to coincide with corresponding indicating means visible in a longitudinal window in said frame.
